UNITED STATES PATENT OFFICE.

GEORGE A. JOHNSON, OF CHICAGO, ILLINOIS, ASSIGNOR TO WILLIAM H. MINER, OF CHAZY, NEW YORK.

RAILWAY-CAR FRICTION-GEAR.

1,255,172.

Specification of Letters Patent.

Patented Feb. 5, 1918.

Application filed December 26, 1916. Serial No. 138,797.

To all whom it may concern:

Be it known that I, GEORGE A. JOHNSON, a citizen of the United States, residing at Chicago, in the county of Cook and State 5 of Illinois, have invented a certain new and useful Improvement in Railway-Car Friction-Gears, of which the following is a full, clear, concise, and exact description, reference being had to the accompanying drawings, forming a part of this specification.

This invention relates to improvements in railway car friction gears.

One object of the invention is to provide a relatively cheap and efficient gear having 15 high capacity with certain release.

Another object of the invention is to provide a friction gear wherein is employed a true, collapsible wedge, as distinguished from so-called differential or combined multiple part main and auxiliary wedges.

Another and more specific object of the invention is to provide a collapsible wedge wherein are employed a series of wedges corresponding to the number of friction 25 shoes and a non-wedging plug mounted between the wedges for the purpose of maintaining the latter in their fully expanded or operative position during the act of compression, the plug being so designed as to 30 be readily releasable upon removal of the pressure, to thereby permit the wedges to collapse and relieve the pressure against the shoes.

In the drawing forming a part of this 35 specification, Figure 1 is a longitudinal, sectional view of a draft rigging showing my improvements in connection therewith, some parts being shown in side elevation. Fig. 2 is a front end elevation of the improved 40 gear. Fig. 3 is a vertical, sectional view showing more particularly the friction elements and taken on the line 3—3 of Fig. 1. Figs. 4 and 5 are detail perspectives of one 45 of the wedges and one of the friction shoes, respectively. And Fig. 6 is a sectional view, partly broken away, similar to Fig. 1 and illustrating another embodiment of the invention.

In said drawing, 10 denotes a center or 50 draft sill to which are secured a rear stop 11 and front stop 12. Coöoperating with the

stops are followers 13 and 14, the latter being inclosed by a yoke 15 that is riveted or otherwise secured to the draw bar 16. The parts of the draft rigging are supported by means of a saddle plate 17. All of the foregoing described structure may be of standard or well known construction.

The improved friction gear, as shown, comprises a preferably cylindrical casting A 60 having an integral friction shell portion 18, integral spring casing 19 and integral rear wall 20. Coöperable with the friction shell 18 is a circularly arranged series of friction shoes 21—21, each having an outer cylindrical surface engaging the interior cylindrical surface of the shell. Each shoe 21, on its interior, is provided with a wedge face 22 arranged at a relatively acute angle with the axis of the gear. Coöperable with 65 the friction shoes and corresponding in number thereto is a series of wedge elements 23—23, each of the latter having an exterior wedge face 24 engaging the corresponding wedge face 22 of a friction shoe. 70 As clearly appears from Figs. 2, 3 and 5, the wedge elements are prevented from circumferential movement with respect to the shoes by the flange portions 25 of the shoes. As appears from Fig. 1, the wedge elements 75 23 are extended forwardly of the ends of the friction shoes and on their inner faces the wedge elements 23 are provided with inclined faces 26 forming a pyramidal shaped recess to accommodate a correspondingly shaped plug 27 which fits loosely therewithin. The plug 27, at its outer end, is provided with a flange 28 which overlaps and normally engages the outer ends of the wedge elements 23, said flange 28 bearing 80 directly against the front follower 14. The plug 27 is also provided with an inwardly extended stem 29 that passes through the wedges and between the inner ends of the friction shoes. At its extreme inner end, 85 the stem 29 is provided with a flange enlargement 30 against which bears the forward end of the inner coil 31 of the spring of the gear. The friction shoes 21 all bear at their inner ends against a washer 32, the latter in turn bearing against the forward 90 end of the outer coil 33 of the spring of

95 100

the gear. The plug and wedge elements 23 (the latter being separated along their radial faces as clearly indicated in Fig. 3), are so designed that the plug 27 merely holds 5 the wedge elements in fully expanded operative condition without any appreciable wedging action therewith, so that, upon compressive action of the gear, there will be no relative sliding or wedging action between the plug and the wedge elements 23.

10 In operation, upon inward movement of the draw bar, pressure will be transmitted through the follower 14 to the flange 28 and from the latter directly to the outer ends 15 of the wedge elements 23 in lines parallel to the axis of the gear. This pressure is transferred from the wedge elements 23 to the friction shoes through the wedge faces arranged at an acute angle to the axis of 20 the gear and finally from the friction shoes radially to the friction shell. Inward movement of the friction elements relative to the friction shell is resisted by the two coils of the spring, the outer coil against the 25 friction shoes and the inner coil against the plug. Upon removal of the pressure, that is, during release, it is apparent that the plug 27 will be immediately disengaged from the wedge elements since there is only a 30 loose engagement therebetween and not a wedging or tight frictional engagement. This disengagement of the plug with respect to the wedge elements, permits the latter to immediately collapse and thus relieve the 35 pressure against the friction shoes. By this arrangement, I am enabled to obtain a friction gear of high capacity since the use of acute wedging angles is permitted and at the same time effecting a positive and certain 40 release.

In the construction illustrated in Fig. 6, the arrangement of friction shell, shoes, washer against the shoes, and outer coil of the spring is the same as for the structure 45 illustrated in the remaining figures. In this modified form, however, the wedge elements 123 are provided on their interior faces with duplicate, inclined surfaces 124 and 124' and the plug 127 is correspondingly formed 50 with duplicate, inclined surfaces 224 and 224'. A washer 140 is also provided against which the inner ends of the wedge elements 123 bear on one side and the outer end of the inner coil 131 of the spring on the other 55 side. In order to hold all the parts in assembled relation, a connecting bolt 141 is provided that extends through the plug and the inner coil of the spring and is loosely connected to the rear end of the combined 60 friction shell and spring casing in a well known manner. The operation of the construction shown in Fig. 6 is similar to that of the construction illustrated in the other figures and will be understood from the 65 preceding description. In both forms, the

angle between the engaging surfaces of the wedge elements and the plug is made relatively blunt in order to prevent the possibility of any undesired wedging action.

Although I have herein shown and described what I now consider the preferred means of carrying out my invention, the same is merely descriptive and I contemplate all changes and modifications that come within the scope of the claims appended hereto.

I claim:

1. In a frictional shock absorbing mechanism, the combination with a friction shell, of friction shoes coöperable with said shell and having interior wedge faces, a spring, a plurality of wedge elements coöperable with said shoes, and means within said wedge elements and coacting therewith to hold the wedge elements in expanded operative position during compressive action of the mechanism and free to move with respect thereto during release, said means having portions overlapping the ends of the wedge elements through which pressure is transmitted to said elements during compressive action.

2. In a frictional shock absorbing mechanism, the combination with a friction shell, of a plurality of friction shoes, a spring, wedge elements coöperable with said shoes, and a plug extending within the shoes and adapted to hold the wedge elements in expanded operative position during compressive action of the gear, said plug having a flange overlapping the ends of said wedge elements and through which pressure is transferred to said elements during the compressive action of the mechanism, said plug being movable independently of said elements during release to thereby permit the wedge elements to collapse.

3. In a frictional shock absorbing mechanism, the combination with a friction shell, of friction shoes coöperable with said shell and having interior wedge faces, a plurality of wedge elements coöperable with said shoes, and means extending within but substantially free from wedging action with respect to said wedge elements, said elements and means acting substantially as a solid wedge during compressive action of the mechanism, spring means for resisting movement of the friction shoes, and a spring directly engaging said means and adapted to move the latter independently of the wedge elements under release.

4. In a frictional shock absorbing mechanism, the combination with a friction shell, of friction shoes coöperable with said shell and having interior wedge faces at an acute angle to the axis of the shell, spring means for directly resisting movement of said shoes, a plurality of wedge elements coöperable and corresponding in number to said

friction shoes, a plug extending within said wedge elements and having a flange at its outer end overlapping the ends of said elements, said plug and elements acting substantially as a solid wedge during compressive action of the gear, and a spring directly engaging the inner end of said plug and

adapted to impart movement thereto independently of the wedge elements during release.

10

In witness that I claim the foregoing I have hereunto subscribed my name this 22d day of Dec., 1916.

GEORGE A. JOHNSON.
